UNITED STATES PATENT OFFICE

CHARLES G. BROSTROM, OF LYNN, MASSACHUSETTS, ASSIGNOR TO UNITED SHOE MACHINERY CORPORATION, OF PATERSON, NEW JERSEY, A CORPORATION OF NEW JERSEY

SKIVING MECHANISM

Application filed May 21, 1927. Serial No. 193,336.

This invention relates to trimming machines for use in the manufacture of shoes and is herein illustrated as embodied in a machine for beveling covers which have been laid upon heels. An embodiment of my invention which will be hereinafter described is particularly designed to skive or to bevel the margins of covering material applied to the breasts of Louis heels. Such heels are made of wood to which is cemented a cover of thin leather, celluloid, or an equivalent, the cover lying smoothly on the sides of the heel with its margins turned over the forward edges of the heel and secured to the breast or forward face of the heel. When the heel has been secured to a shoe, the breast is covered by a thin sheet of leather split from the heel end portion of the shoe sole. This covering sheet should present a smooth finished surface on the breast. Hence it is necessary to bevel the marginal portions of the heel cover which are secured to the breast. Such a beveling or skiving operation is slow, tedious and imperfect when performed by hand, and adds materially to the cost of the shoe. While the hereinafter described machine is illustrated as operating upon covers secured to Louis heels, it will be clear that the machine may be used to bevel or to skive covers laid upon other types of heels.

It is an object of this invention to provide a machine for effectively and expeditiously beveling covers of sheet material which have been applied to rigid bodies such, for example, as heels of shoes.

With this object in view and in accordance with a feature of the invention, the illustrated machine comprises a cutter constructed and arranged to bevel the portions of a heel cover inturned upon a face of a heel and mechanism which is constructed and arranged to guide the heel relatively to the cutter by engagement with the face for progressively presenting said portions of the cover to the cutter for performing the beveling operation.

The illustrated machine is provided with a flexible knife blade, and, in accordance with another feature of the invention, flexing means is provided for engaging opposite

sides of the blade to provide a curved trimming portion well adapted to skive and bevel the marginal portion of a heel cover. Preferably means is also provided for changing the curvature of said portion to suit the requirements of different jobs. In order to guide a heel and the inturned marginal portions of its cover relatively to the cutter for beveling said portions and in accordance with another feature of the invention, the machine is provided with a gage positioned rearwardly of and adjacent to the cutting edge of the knife and constructed and arranged to engage the breast of the heel for guiding the heel past the cutter to bevel the inturned margins. The illustrated gage has a small heel-engaging surface and is so positioned and arranged that the heel may be moved past the cutter, while supported against the gage, in a curved path approximating the heightwise curvature of the breast of a heel and may also be tilted laterally for trimming the upper inturned marginal portions along the projecting breasts of Louis heels.

The mechanism for flexing the band knife by engaging opposite sides of the same is illustrated as being in rolling contact with the knife, and this construction reduces to a minimum the friction between the flexing mechanism and the knife and at the same time maintains the knife well tensioned. In order to centralize the heel being operated upon and to steady the same during the cover-beveling operation and in accordance with another feature of this invention, the illustrated machine is provided with a rest which may be positioned for engagement with a side of the heel as the breast of the heel engages the above-mentioned gage and which assists in centralizing and steadyng the heel as the heel is moved past the cutter during the beveling operation. The rest may be moved widthwise of the heel being trimmed during the trimming operation by mechanism controlled by the leg of the operator, this arrangement leaving the operator free to use both hands in handling the heel.

The herein disclosed method is described and claimed in application for Letters Patent of the United States Serial No. 461,439, 100

which was filed June 16, 1930 in my name and which is a division of the present application.

In one aspect the invention relates to a method of beveling the inturned margins of a heel cover which comprises beveling the two marginal portions on the lower part of the breast of the heel and the two marginal portions on the upper part of the breast of the heel in separate operations. The lower portion of the breast of a Louis heel is commonly concave transversely of the heel, and preferably the two margins at said portion will be beveled simultaneously.

In another aspect the invention relates to a machine for beveling the inturned margins of heel covers and thereby displacing hand work.

The illustrated machine comprises a band knife, a portion of one otherwise straight run of which is maintained flexed to correspond to the concave curvature of the lower portion of the breast of the heel. With this construction the inturned margins of the cover may be beveled, in accordance with the method, by a cut which progresses along both margins from the middle of the breast to the bottom thereof and by two cuts which progress from the middle of the breast respectively along one margin at a time to the top of the breast.

Various advantageous features of my invention will be apparent to one skilled in the art from the disclosure thereof in the following description, and on the drawings of which:—

Figure 1 is a front elevation of a machine embodying my invention.

Figure 2 is a plan view of the same.

Figure 3 is a section on the line 3—3 of Figure 1.

Figure 4 is a detail of a portion of Figure 1 on a larger scale, part of the framework being broken away.

Figure 5 is a fragmentary view of a portion of the sharpening wheel shown in Figure 3 and a cross section of the knife in contact therewith.

Figures 6, 7 and 8 are sections on the lines 6—6, 7—7 and 8—8 respectively, of Figure 4.

Figure 9 is a longitudinal section of a heel showing the action of the knife in skiving the central and lower edge portions of the heel cover on the breast of the heel.

Figure 10 is a section on the line 10—10 of Figure 9, certain parts of the mechanism also being shown in elevation in this figure.

Figure 11 is a section of a heel showing the knife operating on the upper portion of the heel breast.

Figure 12 is a section on the line 12—12 of Figure 11, parts of the mechanism also being shown.

Figure 13 is a fragmentary perspective of the breast of the heel, showing the knife operating along the margin of the heel seat.

Figure 14 is a diagrammatic showing of a band knife locally flexed in a plurality of places for simultaneous use by an equal number of operators.

Referring to the drawings in detail, 20 represents a band knife or flexible cutter having one of its edges sharpened for cutting. As this knife is to be locally flexed in order to present a bulge or convex portion, the band is preferably of relatively thin flexible steel. The band knife 20 may be supported as by a pair of wheels 21, 22 about the peripheries of which the knife is passed, thus forming parallel stretches of knife band between the wheels. Each wheel is preferably formed with a radially extending flange 23, against which the unsharpened edge of the band engages. The wheel 21 may be driven by any suitable means, such as an electric motor 24 which as shown may be connected to suitable reduction gearing indicated at 25 so as to drive the wheel 21 at the speed desired. A shaft 26 is shown connecting the motor with the gearing 25 and a shaft 27 is shown extending from the gearing 25 and supporting the wheel 21 which may be secured thereto as by a set screw 28. The shaft 27 may be supported as desired in a suitable bearing in a standard 29 which is secured to a bench or table 30. The wheel 22 may be supported by a standard 31 the upper portion of which is preferably slotted as at 32 to receive a bearing block 33 in which is journaled a shaft 34 on which is fixed the wheel 22. The block 33 may be moved to different adjustable positions relatively to the standard 31 by turning a hand nut 35 which is in threaded relation with a screw 36 secured to the block 33. Between the wheels 21, 22 a suitable frame member 36 is mounted on the bench 30. This member as shown in Figure 4 may be shaped with a centrally arched portion 37 through which is passed a member 38 having a reduced screw-threaded portion 39. The lower end of the member 38 is forked to receive a roller or presser foot 40 which is suitably journaled therein. An adjusting nut 41 is fitted into a suitable recess in the arched portion 37 of the frame member, the threaded stem 39 being in threaded engagement with the nut 41. As the nut is held against longitudinal motion by the recess in which it is located, the rotation of the nut will result in an up or down motion of the member 38 and thus of the roller 40. The members supporting the roller 40 are so arranged that the lower margin of the roller may be adjustably moved below the straight path of the lower stretch of the band knife between the wheels 21, 22. The roller 40 is also located directly above the band knife 20 so that it rests upon the upper face of the knife and locally flexes downwardly the portion of the knife adjacent thereto by an amount depending upon its adjustment through the adjusting nut 41. A

120

125

130

suitable guard and gage member 42, shown in Figs. 4 and 6, may be attached to the member 38, this member extending downwardly as shown in Figure 6 with a horizontal portion 5 the upper surface of which engages the under side of the band knife 20 at a point directly opposite to the point of engagement of the roller 40 with the knife and the under surface of which serves as a gage against 10 which the breast of a heel 53 engages as will later appear. The end portion of the guard 42 is preferably beveled as at 43, the bevel registering with a similar bevel 44 on the knife 20 which forms the cutting edge thereto. The guard 42 is not essential to the operation of the mechanism but its use makes possible speedier work. It also serves as a gage to regulate the depth of the cut and is a valuable aid in securing uniform trimming 20 action. On either side of the roller 40 and engaging against the under face of the band knife are a pair of horizontal guide rollers 45, 46. These rollers are disposed alongside the straight path of the stretch of knife between the wheels 21, 22, and cooperate with the roller 40 to flex the knife locally around a portion of the periphery of the roller 40. The rollers 45, 46 may be mounted for adjusting movement along the path of the knife. 30 To this end, they may be journaled in frame members one of which is indicated at 47, slidably supported on the bench 30 and adapted to be moved to adjusted position as by a suitable screw 48. By vertical adjustment 35 of the roller 40 and by horizontal adjustment of the rollers 45, 46, the amount of flexure of the knife at the periphery of the roller 40 may be regulated within limits. Vertical guide rollers 49, 50 may be provided adjacent to 40 the rollers 45, 46 respectively to keep the knife horizontally aligned with the roller 40. Figures 9-12 present various sections of a typical Louis heel on which the machine as described is adapted to operate. As shown in 45 Figures 10 and 12, the lower part of the heel breast 51 is relatively flat or slightly concave, the upper part being slightly convex. A covering sheet 52 is wrapped about and cemented to the sides of the wooden heel 53, 50 the marginal portions of the sheet 52 being secured to the heel breast as at 54 (Figure 13). In order to bevel the marginal portions 54 to a thin edge without cutting the wood of the heel, it is necessary, as shown in Figure 10, to use a curved blade which will be substantially tangent to the center of the heel breast when operating on the heel. The size and shape of the heel to be operated upon will determine the adjustment of the guide rollers 40, 45 and 46 upon which depends the curvature of the blade 20 at the point of application of the work. The center and lower portions of a Louis heel breast are relatively narrow and flat or slightly concave laterally 55 so that the blade 20 is preferably flexed to bevel both edges 54 in one operation along these parts of the heel as shown in Figures 9 and 10. The sharp edge of the band knife is turned away from the operator who draws the heel toward him as the knife cuts. In 70 beveling the margins 54 on the upper portion of the heel breast, as shown in Figures 11 and 12, where the breast is convex laterally, the edge on each side of the heel breast must be beveled separately. In order to steady the heel and to guide it during the action of the knife, a guide member, gage or rest 55 is provided, which rest is constructed and arranged to engage a side of the heel and cooperates with the member 42 for locating the heel relatively to the knife as the heel is moved past the knife to perform the trimming operation. The illustrated rest 55 comprises a horizontal bar having a sloping end 56 in which is fixed a rod 57 which engages the blunt edge of the band knife and thus serves to take the lateral thrust caused by the friction of the knife blade when cutting on the heel breast. Since the heel varies in width so that the relation of the knife to the position of the heel as a whole changes as different portions of the heel breast are operated on, the guide member 55 is preferably made movable. Figure 95 12 illustrates two positions of the guide member which it will assume when the marginal portions 54 on the two sides of the upper portion of the heel breast are successively operated on. In order to facilitate the adjustment of the guide 55 without interrupting the work of the operator, a suitable lever 58 is provided with a fulcrum 59 on the edge of the bench 30. The lower portion of the lever 58 may be operated by the knee or foot of an operator. The upper portion may be provided with a slot 60 in which rides a pin 61 which is secured in the guide bar 55. A suitable spring 62 may be provided as shown in Figures 1 and 4, this spring being secured as 100 at 63 to the bar 55, and its opposite end 64 to the frame member 36. The spring 62 is preferably under tension so as to pull the bar 55 toward the right as shown in Figures 1 and 4. Pressure of the operator's knee against the lever 58 will push the bar 55 toward the left against the tension of the spring. Hence the position of the guide is constantly and easily controlled and shifted by the operator as the heel is being moved for the skiving of different portions so that the flexed portion of the knife may be held progressively related to the heel as portions of different widths are brought into contact with the bar 55, leaving both of the operator's hands free to manipulate the work. The machine may be operated as follows: 105

The operator takes a heel and holds it under the knife below the roller 40, the bottom of the heel being away from him. The side of 110

115

120

125

130

the heel is held against the guide bar 55 and the breast of the heel is held against the member 42 for positioning the heel relatively to the flexed portion of the knife, the guide 6 being moved by the operator's knee to center the heel beneath the roller 40. The breast of the heel is then brought into contact with the knife at or near its center, as shown in Figure 9, and the heel is drawn toward the 10 operator during which movement the knife bevels both marginal portions 54 of the heel cover to the bottom of the heel, the guide 55 being shifted gradually meanwhile to maintain the heel centered beneath the roller 40. 15 The heel is then reversed and held with its top away from the operator. It is brought against the knife as shown in Figures 11 and 12 to bevel each margin 54 separately, the heel being drawn toward the operator during 20 the cutting action of the knife.

In addition to beveling the end edges 54 of the cover 52 on the heel, the apparatus may be used to bevel the marginal portion 65 of the cover which (as shown in Figures 9 and 25 11) is turned over the seat face of the heel. The action of the mechanism in beveling this marginal portion 65 on the heel seat is similar to its action in beveling the marginal portion 54 on the heel breast.

30 A grinder 71 is adapted to be caused to engage the knife 20, when desired, in the manner shown best in Figure 5. The grinder is fast to the shaft of a small electric motor 73 said motor being mounted in a carrier 35 which is pivoted to the frame of the machine at 75. A spring, attached at its ends to the motor carrier and extending down around the bottom of a rigid bracket 77, tends at all times to swing the motor, and with it the 40 grinder, away from the knife. An adjusting screw 79, threaded through the bracket and contacting with the under side of the motor carrier furnishes means for moving the grinder into contact with the knife when 45 desired.

In order to avoid unnecessary duplication of parts in cases where a plurality of operators are engaged in beveling the edges of heel covers, I may provide a long band knife 50 as shown in Figure 14, this knife being long enough to pass over a pair of wheels 21, 22 which are sufficiently spaced to allow room for a plurality of operators side by side at the working bench between the wheels. 55

Opposite each operator a set of guide wheels 40, 45, 46 may be provided, the mounting and adjustment of the guide wheels being as previously described.

60 Having thus described certain embodiments of my invention, it should be evident to those skilled in the art that various changes and modifications may be made therein without departing from its spirit or 65 scope as defined by the appended claims.

I claim:

1. In a machine of the class described, an elongated flexible cutter having a cutting edge, means for carrying the cutter and for moving it longitudinally of itself, guiding 70 rolls engaging one side of the cutter, means engaging the other side of the cutter for maintaining said cutter locally flexed at a point at which work may be presented thereto, and means for adjustably varying the 75 flexure of the cutter at said point.

2. In a machine of the class described, a pair of wheels, an endless band knife carried by said wheels with stretches therebetween, a pair of guide rollers engaging one 80 side of said knife along the straight path of one of the stretches, a deflecting roller positioned to engage the opposite side of said knife at a point between said guide rollers, and means for adjusting the deflecting roller 85 transversely of the knife.

3. In a machine of the class described, a band knife, knife guiding means engaging one side of the knife, means engaging the other side of the knife for maintaining a 90 portion of said knife locally flexed at points where work may be presented thereto, other means for driving the knife longitudinally of itself, and a movable guide rest for the work 95 adjacent to said point of flexure of the knife.

4. In a machine of the class described, a band knife, means for driving said knife longitudinally of itself, a pair of spaced guide rollers positioned to engage said knife on the same side thereof, a flexing roller between 100 said guide rollers and engaging the opposite side of said knife, means for adjustably moving said guide rollers along the path of the knife, and means for adjustably moving said flexing roller transversely to the path of the 105 knife.

5. In a machine of the class described, a band knife, means for driving said knife longitudinally of itself, spaced guiding means engaging said knife on one side thereof, a flexing member engaging the knife on the opposite side thereof and at a point between said guiding means, and a guard member engaging said knife at a point directly 110 opposite to the flexing member.

6. In a machine of the class described, a band knife, means for moving said knife longitudinally of itself, means engaging opposite sides of the knife for maintaining said knife locally flexed at a plurality of separated points to form an undulatory knife surface at which points separate pieces of work may be presented simultaneously, and means for adjustably varying the flexure at each of 115 said points.

7. A machine of the class described having, in combination, a band knife, means for operating the knife, and means for supporting a portion of the knife at a selected locality of one run of the knife for presentation 120 130

- of a piece of work thereto, there being a free and unobstructed space on three sides of the knife at this locality whereby the operator may stand at the rear of the knife, present the work to the edge of the knife and draw the work toward him with either the top or the bottom of the work toward him as may be desired.
8. A machine of the class described having, in combination, a band knife, means for operating the knife, and means for supporting a portion of the knife in flexed condition at a selected locality of an otherwise straight run of the knife for presentation of a piece of work thereto, there being a free and unobstructed space on three sides of the knife at this locality whereby the operator may stand at the rear of the knife, present the work to the edge of the knife and draw the work toward him with either the top or the bottom of the work toward him as may be desired.
9. A machine for beveling the inturned margin of a heel cover upon the breast of a heel having in combination a cutter to which the heel is presented and past which it is moved, a guide adapted to engage the side of the heel to facilitate the presentation of the inturned margin to the edge of the cutter, and means for operating the cutter.
10. A machine for beveling the inturned margin of a heel cover upon the breast of a heel having in combination, a cutter to which the heel is presented and past which it is moved, a guide adapted to engage the side of the heel to facilitate the presentation of the inturned margin to the edge of the cutter, means for operating the cutter, and means for changing the position of the guide during the operation of the cutter.
11. A machine for beveling the inturned margin of a heel cover upon the breast of a heel having in combination a knife, a guide for facilitating the presentation of the inturned margin to the knife, and means for operating the knife.
12. A machine for beveling the inturned margin of a heel cover upon the breast of a heel having in combination a knife, a guide for facilitating the presentation of the inturned margin to the knife, and means for causing the knife to produce a draw cut.
13. A machine for beveling the marginal portion of a covering applied to a heel having, in combination, a flexible cutter mounted for movement longitudinally of itself, means to flex the cutter at a portion arranged so that the heel may be presented to the cutter for beveling the marginal portion of the heel covering, means to guide the heel past the cutter, and means to vary the flexure of the cutter at its flexed portion.
14. A machine for beveling the marginal portion of a covering applied to a heel having, in combination, a band knife, means for carrying the band knife and for moving it longitudinally of itself, a pair of guide rolls engaging one side of the band knife, a presser engaging the opposite side of the band knife and constructed and arranged for cooperation with guide rolls to flex a portion of the cutter for facilitating the presenting of the heel to the band knife to bevel the marginal portion of the heel covering, and means to vary the flexure of the knife at its flexed portion.
15. A machine for beveling the marginal portion of a heel covering upon the breast of a heel having, in combination, a band knife mounted for rotation longitudinally of itself, a pair of guide rolls arranged to engage one side of the band knife, a presser roll arranged to engage the opposite side of the band knife for flexing a portion of the knife to facilitate the presenting of a heel to the band knife for beveling the marginal portion of the heel covering, means for varying the amount of the flexure at the flexed portion of the knife, and means for guiding the heel past the flexed portion of the knife as the beveling operation progresses.
16. A machine for beveling the marginal portion of a heel covering upon the breast of a heel having, in combination, a band knife, rolls for guiding the band knife, a presser roll arranged to flex a portion of the knife in such a manner that the heel may be presented to the flexed portion of the knife for beveling the marginal portion of the heel covering upon the breast of the heel, means for varying the flexure at the flexed portion, a member serving as a guard for the knife and also arranged to support the heel breast during the beveling of the marginal portion of said covering, and means to engage a side of the heel as the heel is moved past the flexed portion of the knife to carry out the beveling operation.
17. A machine for beveling the marginal portion of a heel covering applied to a heel having, in combination, a flexible cutter having a cutting edge mounted for movement longitudinally of itself, means for engaging one side of the cutter, a presser for engaging the other side of the cutter at a point so as to form a flexed portion of the cutter arranged to bevel the marginal portion of the heel covering as the heel is moved past the cutter, means associated with the presser arranged to engage a surface of the heel to facilitate the guiding of the heel past the flexible portion of the cutter, and other means for engaging another surface of the heel to assist in correctly positioning the same relatively to the cutter as the trimming operation progresses.
18. A machine for beveling the inturned marginal portion of a heel covering upon the breast of a heel having, in combination, a flexible cutter mounted for movement longitudinally of itself, means for engaging one

side of the cutter, a presser for engaging the other side of the cutter at a point so as to form a flexed portion of the cutter arranged to bevel the marginal portion of the heel covering as the heel is moved past the cutter, means associated with the presser arranged to engage the breast of the heel for guiding the heel past the flexible cutter, and an adjustable gage to engage a side of the heel for facilitating the correct positioning of the heel relatively to the cutter as the trimming operation progresses.

19. A machine for beveling the marginal portion of a heel covering applied to a heel having, in combination, a band knife, means for guiding the knife, a presser member arranged to engage a side of the knife to flex a portion of the knife, said portion being constructed and arranged to bevel the marginal portion of the heel covering as the heel is moved past the knife, and a combined knife guard and gage associated with the presser member and located at the side of the cutter opposite the side of the cutter which the presser member engages, said combined knife guard and gage being constructed and arranged to engage the breast of the heel as the beveling operation progresses.

20. A trimming machine having, in combination, means comprising a cutter having a curved cutting edge constructed and arranged to reduce the thickness of the marginal portions of an inturned heel cover laid upon the breast of a heel, and means for guiding the heel relatively to the cutter as the heel is moved past the cutter for reducing the thickness of the marginal portions of the cover.

21. A trimming machine having, in combination, a cutter having a curved cutting edge movable lengthwise of itself and constructed and arranged to reduce the thickness of the inturned marginal portions of a heel side cover laid upon a concave breast of a heel, and means for guiding the heel relatively to the cutter as the heel is moved past the cutter for reducing the thickness of said inturned marginal portions of the cover.

22. A trimming machine having, in combination, a cutter constructed and arranged to bevel the marginal portions of a heel cover inturned upon a face of a heel, means constructed and arranged to guide the heel relatively to the cutter by engagement with said face thereby progressively to present said portions of the cover to the cutter to bevel the same, and means for operating the cutter.

23. A machine for operating upon an inturned marginal portion of a heel cover applied to the breast of a heel having, in combination, a knife for beveling said marginal portion of the heel cover, means for positioning the heel relatively to the knife as the heel and the knife are moved relatively to each

other to bevel said marginal portion, and means for operating the knife.

24. A machine for operating upon an inturned marginal portion of a heel cover laid upon a face of a heel having, in combination, 70 a cutter mounted for movement lengthwise of its cutting edge for beveling said marginal portion of the heel cover, means for positioning the heel relatively to the cutter as the heel and the cutter are moved relatively to each other to bevel said marginal portion, and means for operating the cutter.

25. A trimming machine having, in combination, a flexible cutter constructed and arranged to bevel the marginal portions of a heel side cover laid upon the breast of a heel, means for varying the flexure of said cutter, and a gage constructed and arranged to guide the heel relatively to the cutter by contacting with the breast of the heel in order progressively to present the marginal portions of the cover laid upon the breast of the heel to the cutter for beveling said portions.

26. A trimming machine having, in combination, a flexible knife mounted for movement lengthwise of itself and constructed and arranged to bevel the inturned marginal portions of a heel side cover laid upon the breast of a heel, a gage constructed and arranged to engage the breast of the heel between said inturned margins for guiding the heel relatively to the cutter to present said inturned marginal portions to the cutter, and means for operating the cutter.

27. A trimming machine having, in combination, a flexible cutter constructed and arranged to bevel the inturned marginal portions of a heel cover laid upon the breast of a heel, means for flexing a portion of the cutter, and means for engaging the breast and a side of the heel for positioning the same relatively to a flexed portion of the cutter to bevel the inturned margins of the cover as the heel is moved past the cutter.

28. A trimming machine having, in combination, a cutter comprising a curved cutting edge movable lengthwise of itself, means for flexing a portion of the cutter, and means for engaging angularly disposed surfaces of a shoe part having a cover secured thereto for positioning the shoe part relatively to the flexed portion of the cutter to bevel the cover as the shoe part and the knife are moved relatively to each other.

29. A trimming machine having, in combination, a band knife, means for engaging angularly disposed surfaces of a shoe part having a cover laid thereon for positioning the shoe part relatively to the band knife while the band knife bevels said cover upon said shoe part as the shoe part is moved past the cutter, and means for operating the cutter.

30. A trimming machine having, in combination, a curved cutter constructed and arranged to bevel the marginal portions of a

- heel cover inturned upon a concave face of a heel and terminating within said concave face of the heel, and a gage constructed and arranged to guide the heel relatively to the cutter by engagement with said concave face for progressively presenting said portions of the cover to the cutter. 5
31. A trimming machine having, in combination, a flexible cutter constructed and arranged to bevel the marginal inturned portions of a heel side cover laid upon the breast of a heel, means for varying the flexure of said cutter, and a gage constructed and arranged to engage a limited portion of the breast of the heel for guiding the heel relatively to the cutter and to permit the heel to be freely tilted laterally of itself as the marginal portions are progressively presented to the cutter. 10
32. A machine for operating on the inturned marginal portions of a heel side cover laid upon the breast of a heel having, in combination, a flexible knife, means for flexing a portion of the knife, means for engaging a side and the breast of the heel for positioning the same relatively to the flexed portion of the knife to bevel said marginal portions as the heel and the knife are moved relatively to each other, and means for operating the knife. 15
33. A machine for operating on the inturned marginal portions of a heel cover laid upon the breast of a heel having, in combination, a band knife, means for flexing a portion of the knife, a gage for engaging the breast of the heel, a gage for engaging a side of the heel, said gages being constructed and arranged to position the heel relatively to the flexed portion of the knife and to guide the heel past said portion to bevel the inturned marginal portions upon the breast of the heel as the heel is moved past the knife, and means for operating the knife. 20
34. A machine for operating on the inturned marginal portions of a heel cover laid upon the breast of a heel having, in combination, a band knife, means for flexing a portion of the knife and for varying the curvature of said portion, a gage for engaging the breast of the heel, a gage for engaging a side of the heel, said gages being constructed and arranged to position the heel relatively to the flexed portion of the knife and to guide the heel past said portion to bevel the inturned marginal portions upon the breast of the heel as the heel is moved past the knife, and means for operating the knife. 25
35. A machine for operating on the inturned marginal portions of a heel cover laid upon the breast of a heel having, in combination, a band knife, means for flexing a portion of the knife, a gage for engaging the breast of the heel to determine the position of the heel toward and away from the knife, a gage for engaging a side of the heel to cen- 30
- tralize the heel relatively to the flexed portion of the knife and mounted for movement toward and away from the first-named gage, said gages being constructed and arranged to guide the heel as it is moved past the flexed portion of the knife for beveling the inturned marginal portions of the cover laid upon the breast of the heel, and means for operating the knife. 70
36. A trimming machine having, in combination, a cutter movable lengthwise of its cutting edge for beveling the inturned marginal portions of a heel side cover laid upon the breast of a Louis heel, means constructed and arranged to guide the heel relatively to the cutter by engagement with said breast as the heel is moved past the cutter for beveling said marginal portions, and means for operating the cutter. 75
37. A trimming machine having, in combination, a cutter movable lengthwise of itself and constructed and arranged to bevel the marginal portions of a heel cover laid upon a cupped face of a heel, and a gage constructed and arranged to guide the heel past the cutter, permitting the heel to be moved in a curved path while in engagement with the face of the heel thereby progressively to present said portions of the cover to the cutter for beveling said portions. 80
38. A trimming machine having, in combination, a curved cutter movable lengthwise of itself and constructed and arranged to bevel the inturned marginal portions of a heel side cover laid upon the breast of a Louis heel, and a gage spaced from the cutting edge of the cutter and constructed and arranged progressively to engage the breast of the heel and to permit the heel to be tilted heightwise and widthwise of itself as it is moved past the cutter thereby beveling said marginal portions of the cover. 85
39. A trimming machine having, in combination, a cutter having a curved cutting edge movable lengthwise of itself and constructed and arranged to bevel the marginal portions of a heel cover inturned upon a face of a heel, means for flexing a portion of the cutter, and a gage independent of said means constructed and arranged to guide the heel relatively to the cutter by engagement with said face to present said portions of the cover to the cutter for beveling said marginal portions. 90
40. A trimming machine having, in combination, a flexible cutter movable lengthwise of its cutting edge and constructed and arranged to bevel the marginal portions of a heel cover inturned upon the breast of a heel, means for varying the flexure of said cutter, and a gage having a shoulder positioned adjacent to the cutting edge of the cutter and adjacent to the plane of movement of the cutter, said shoulder being constructed and arranged to guide the heel relatively to the 100

- cutter and to permit the heel to be moved past the cutter in a path corresponding to the heightwise curvature of the breast of the heel.
41. A trimming machine having, in combination, a band knife constructed and arranged to bevel the marginal portions of a heel cover inturned upon the breast of a heel, means for flexing a portion of the cutter to which the heel to be operated upon is presented and a gage having a shoulder provided with a small gaging surface positioned adjacent to the cutting edge of the knife and also positioned adjacent to the plane of the knife, said shoulder being constructed and arranged to permit the heel to be moved past the cutter in a path corresponding to the heightwise curvature of the heel and also to permit the heel to be laterally tilted as it is moved past the cutter for beveling said marginal portions of the cover.
42. A trimming machine having, in combination, a flexible knife movable lengthwise of itself, a presser-foot constructed and arranged to engage one side of the knife for flexing a portion of the knife, and a gage positioned at the opposite side of the knife and substantially opposite to the presser-foot and constructed and arranged for engagement with the breast of a heel the marginal portions of the side cover of which have been inturned upon the breast of the heel for guiding the heel past the cutter to bevel said marginal portions.
43. A trimming machine having, in combination, a band knife, a presser-foot constructed and arranged to engage one side of the knife for flexing a portion of the same, a gage located at the opposite side of the knife and adjacent to the cutting edge of the knife as well as substantially opposite to the presser-foot, said gage being constructed and arranged for engagement with a heel the marginal portions of the side cover of which have been inturned upon the breast of the heel for guiding the heel in a curved path past the cutter to bevel said marginal portions of the cover upon the breast of the heel.
50. In testimony whereof I have affixed my signature.

CHARLES G. BROSTROM.

CERTIFICATE OF CORRECTION.

Patent No. 1,834,139.

December 1, 1931.

CHARLES G. BROSTROM.

It is hereby certified that error appears in the printed specification of the above numbered patent requiring correction as follows: Page 2, line 4, beginning with the words "In one aspect" strike out all to and including the word "breast." in line 30; and that the said Letters Patent should be read with this correction therein that the same may conform to the record of the case in the Patent Office.

Signed and sealed this 12th day of July, A. D. 1932.

(Seal)

**M. J. Moore,
Acting Commissioner of Patents.**
